UNITED STATES PATENT OFFICE.

OLIVER HAGRUP ERIKSEN, OF ORLAND, CALIFORNIA.

CARPENTER'S CLAMP.

1,259,218.

Specification of Letters Patent. Patented Mar. 12, 1918.

Application filed November 27, 1917. Serial No. 204,268.

To all whom it may concern:

Be it known that I, OLIVER HAGRUP ERIKSEN, a citizen of the United States, residing at Orland, in the county of Glenn, State 5 of California, have invented a new and useful Carpenter's Clamp; and I do hereby declare the following to be a full, clear, and exact description of the invention, such as will enable others skilled in the art to which 10 it appertains to make and use the same.

The present invention relates to certain new and useful improvements in carpenters' clamps, and has for its object to provide a device of this character which embodies 15 novel features of construction whereby the articles to be clamped can be securely gripped, and which can be used in many places where the ordinary form of clamp with its laterally projecting handles could 20 only be used with great inconvenience.

Further objects of the invention are to provide a carpenter's clamp which is comparatively simple and inexpensive in its construction, which can be easily manipulated, which is free from lateral protections and can be used in confined places 25 where there would not be room for the ordinary carpenter's clamp, and which can be adjusted to tightly grip the articles to 30 which it is applied.

With these and other objects in view, the invention consists in certain novel combinations and arrangements of the parts as will 35 more fully appear as the description proceeds, the novel features thereof being pointed out in the appended claims.

For a full understanding of the invention, reference is to be had to the following description and accompanying drawings, in 40 which:—

Figure 1 is a side elevation of a carpenter's clamp constructed in accordance with the invention, the jaws being in an open position and parts being broken away and 45 shown in section to illustrate more clearly the details of construction.

Fig. 2 is a side view of the carpenter's clamp with the jaws in a closed position.

Fig. 3 is a transverse sectional view on 50 the line 3—3 of Fig. 1.

Fig. 4 is a plan view of the gripping end of one of the jaw members, showing one arrangement of the removable gripping block.

55 Fig. 5 is a similar view showing another

arrangement of the removable gripping block.

Fig. 6 is a transverse sectional view through the gripping end of one of the jaws, said view being taken on the line 60 6—6 of Fig. 1.

Corresponding and like parts are referred to in the following description and indicated in all the views of the drawings by the same reference characters. 65

Referring to the drawings, the numeral 1 designate a pair of jaw members which have an elongated formation and are arranged in an opposed and parallel relation, said jaw members being movable toward 70 and away from each other for the purpose of causing the gripping ends thereof to forcibly engage any members or articles which it may be desired to clamp together. Arranged between the jaw members at one 75 end thereof, and having a parallel relation thereto, is an operating shaft 2 which is provided with right hand threads 2^a and left hand threads 2^b, the end of the shaft extending beyond the rear ends of the jaws 80 and terminating in a handle 3. A pair of collars 4 are mounted upon the right hand threads 2^a of the operating shaft, opposite sides of the collars being pivotally connected at 5 to toggle levers 6 which have the 85 outer ends thereof received within recessed portions 7 of the jaw members 1 and pivotally connected to the said jaw members by means of suitable pins 8. A third collar 9 is mounted upon the left hand threads 2^b 90 of the operating shaft 2 and pivotally connected at 10 to links 11 which are inclined reversely with respect to the toggle levers 6 and pivotally connected at their outer ends to one of the pins 8. With this construction 95 it will be obvious that by rotating the operating shaft 2 the two collars 4 will be moved longitudinally thereon in one direction and the collar 9 moved upon the shaft in the opposite direction, thereby causing 100 the toggle levers to either force the jaw members 1 apart or draw them toward each other. The recessed portions 7 of the jaw members are arranged to house the toggle levers 6 and operating shaft 2 when the 105 jaw members are drawn completely together, as indicated by Fig. 2.

The jaw members may be constructed either of wood or metal, although it would probably be preferable to form them of 110

metal and provide the gripping ends thereof with removable wooden blocks 12, said blocks being interchangeable and being also adjustable to different positions so that the articles to be engaged by the clamp can be gripped in the most effective manner. In the present instance the gripping blocks 12 are fitted within notches 13 in the ends of the jaws 1 and provided upon their lower faces with longitudinally extending dove-tail ribs 14 which are adapted to slide into either set of dove-tail grooves 15 or 16 of the jaw members 1. The dove-tail grooves 15 extend parallel to the jaws, while the grooves 16 are arranged transversely with respect thereto and intersect the grooves 15 at right angles. With this construction it will be obvious that the gripping blocks 12 can either be arranged parallel to the jaw members 1, as indicated by Fig. 4, or transversely with respect thereto, as indicated by Fig. 5, thereby enabling the device to be adjusted in such a manner as to grip the articles to be clamped in the most effective manner. Owing to the absence of laterally projecting handles and screws it will be understood that the device can be used in confined spaces where the ordinary carpenter's clamp could only be used with inconvenience and difficulty.

Having thus described the invention, what I claim as new and desire to secure by Letters Patent, is:—

1. A clamp of the character described, including a pair of opposed and substantially parallel elongated jaw members, an adjusting rod arranged between and parallel to the jaw members and having right and left hand threaded portions, a pair of collars en-

gaging one threaded portion of the adjusting rod, toggle levers connecting the collars to the jaws, a third collar arranged upon the opposite threaded portion of the adjusting rod, a set of links inclined reversely with respect to the toggle levers and pivotally connecting the third collar to the jaw members so that by rotating the adjusting rod the jaw members will be moved toward or away from each other by the action of the toggle levers.

2. A clamp of the character described including a pair of opposed and substantially parallel elongated jaw members, said jaw members having the inner faces thereof recessed at one end, an adjusting rod arranged between the recessed ends of the jaw members and provided with right and left hand threaded portions, a pair of collars engaging one threaded portion of the rod, toggle levers pivotally connecting the collars to the jaw members, a third collar engaging the other threaded portion of the rod, links inclined reversely with respect to the toggle levers and pivotally connecting the third collar to the jaw members, so that by rotating the adjusting rod in opposite directions the jaw members can be moved toward and away from each other, the adjusting rod and toggle levers being received within the recessed portions of the jaws when the jaws are brought together.

In testimony whereof I have signed my name to this specification in the presence of two subscribing witnesses.

OLIVER HAGRUP ERIKSEN.
